John Stewart,
ATTORNEY.

UNITED STATES PATENT OFFICE.

ALBERT WANNER, JR., OF NEW YORK, N. Y.

FITTING-STOOL.

1,310,108.

Specification of Letters Patent. Patented July 15, 1919.

Application filed September 21, 1916. Serial No. 121,412.

To all whom it may concern:

Be it known that I, ALBERT WANNER, Jr., a citizen of the United States, residing at New York city, in the county of New York 5 and State of New York, have invented certain new and useful Improvements in Fitting-Stools, of which the following is a specification.

In an application for Letters Patent filed 10 by me April 14, 1916, Serial No. 91,068, I have described and claimed a fitting stool whereon a person may rest his foot while having shoes fitted, and on which the person fitting the shoes may sit in which one of 15 the principal features was a pair of arched side members each shaped (in that case by bending) to substantially the form of a curve of a conic section and having one side of its arch arranged at a gradual incline and 20 the other more precipitate.

The object of the present invention is to simplify and reduce the cost of manufacture of fitting stools of this class and make them more durable and also stronger. This I accomplish by forming the side members each 25 of a plate of laminated sheet material, preferably cross-grained wood, having the layers thereof cemented or otherwise secured together, each member including an arched 30 portion shaped to substantially the form of the curve of a conic section and having one side of its arch arranged at a gradual incline and the other more precipitate. In the 35 preferred form, where there are for each arched member one or more upstanding side standards to which to attach the connecting means for said members, as the seat and foot-rest, each said member includes such side standard or standards as an integral 40 or projecting part of a side-forming element of the stool.

I now proceed to describe my invention in detail, having reference to the preferred form thereof shown in the accompanying 45 drawing, wherein,

Figure 1 is a side elevation of the improved stool;

Fig. 2 is a side elevation and Fig. 3 an end elevation of one of the side elements of 50 the stool;

Fig. 4 is a sectional view on line 4—4 of Fig. 1; and,

Fig. 5 is a plan, partly broken away.

In the drawings, *a a* are the side elements, 55 each being a plate composed of laminated

sheets *b* of suitable material, preferably cross-grained wood, cemented together. In side elevation, in which the layers stand in vertical planes, the plate is arched, as shown, the arch conforming to substantially 60 the form of the curve of a conic section and having one side thereof arranged at a gradual incline, as at *c*, and the other more precipitate.

In the preferred construction, each plate 65 includes upstanding standards *d* and *e*, the former at the high part and the latter on the gradual-incline part of the arch. The top of the standard *d* is horizontal and the top of the standard *e* inclined more or less 70 to the same inclination as the inclined portion *c* of the arch.

The side elements *a a* are substantial counterparts of each other.

On the top of the standards *d* of the two 75 side elements *a a* is secured a seat proper *f*, which may be upholstered, as shown in Fig. 5. On the tops of the standards *e* is secured a foot rest proper *g*, which may be equipped near its lower edge with a heel 80 supporting ridge *h*.

As in my aforesaid application, a receptacle, open toward the seat, so as to be readily accessible therefrom, may be formed below the foot-rest *g*. This is composed of the 85 front wall *i* and bottom wall *j* extending from one to the other of the side elements *a a* and suitably secured thereto, as by having their edges glued in grooves therein (Fig. 4). 90

The said receptacle and a cross-piece *k*, connecting the rear portions of the side elements, serve to brace and give rigidity to the entire structure.

Semblance of individuality of formation 95 may be imparted to the side elements, and an ornamental finish imparted thereto, by routing their outer faces, as indicated at *l* and *m* in the drawing.

The structure, already strong and exceedingly durable, while light in weight and of convenient form to pick up or move about over the floor, on account of the arch formation of its base portion already disclosed in my aforesaid application, has increased 100 strength and durability and is capable of being manufactured at the minimum of cost, due to the side elements being composed of laminated sheet material having its layers arranged in vertical planes. 105

Having thus fully described my invention, what I claim as new and desire to secure by Letters Patent is:—

An article of manufacture of the class 5 described consisting of two substantially counterpart upright side elements each composed of laminated sheet material having its layers arranged in vertical planes and each including an arched portion shaped to substantially the form of the curve of a conic

section and having one side of its arch arranged at a gradual incline and the other more precipitate, in combination with a foot-rest member and a seat member connecting said elements and arranged respectively over the gradual-incline and high parts of their arched portions. 15

In testimony whereof I affix my signature.

ALBERT WANNER, JR.

Copies of this patent may be obtained for five cents each, by addressing the "Commissioner of Patents, Washington, D. C."
